(57) **CLAIM**

The ornamental design for a light, as shown and described.

DESCRIPTION

FIG. 1 is a perspective view of a light showing our new design;

FIG. 2 is a top view thereof, the bottom view being a mirror image;

FIG. 3 is a right side view thereof, the left side being a mirror image;

FIG. 4 is a rear view thereof; and,

FIG. 5 is a front view thereof.

In the drawings, the broken lines show portions of a light that form no part of the claimed design.

The drawings include surface shading which illustrates contour and not surface ornamentation.
